(57) **CLAIM**

The ornamental design for a support leg, as shown and described.

DESCRIPTION

FIG. 1 is a side perspective view of a support leg in accordance with a first embodiment of the invention.

FIG. 2 is a top view of the support leg of FIG. 1; and, FIG. 3 is a side view of the support leg of FIG. 1.

The broken lines shown in the figures are for illustrative purposes only and form no part of the claimed design.
